(57) **CLAIM**

The ornamental design for an electrical connector, as shown and described.

DESCRIPTION

FIG. 1 is a front, right side and top perspective view of an electrical connector in accordance with an embodiment of my new design;

FIG. 2 is a front, right side and bottom perspective view of the electrical connector in accordance with the embodiment of my new design;

FIG. 3 is a front elevation view of the electrical connector in accordance with the embodiment of my new design;

FIG. 4 is a rear elevation view of the electrical connector in accordance with the embodiment of my new design;

FIG. 5 is a left side view of the electrical connector in accordance with the embodiment of my new design, a right side view being a mirror image thereof;

FIG. 6 is a top plan view of the electrical connector in accordance with the embodiment of my new design; and,

FIG. 7 is a bottom plan view of the electrical connector in accordance with the embodiment of my new design.

The broken line portion of the drawings is included to show portions of the article that forms no part of the claimed design.

1 Claim, 3 Drawing Sheets
